MUZZLE BRAKE

Clifford L. Ashbrook, 5027 Cheena St., and Wilson G. Wing, 33 E. Rivercrest, both of Houston, Tex.

Filed Dec. 4, 1962, Ser. No. 72,718

Term of patent 14 years

(Cl. D30—1)

FIG. 1 is a perspective view of the muzzle brake embodying our new design;

FIG. 2 is an end view of said muzzle brake;

FIG. 3 is a top view of said muzzle brake; and

FIG. 4 is a side view of said muzzle brake.

We claim:

The ornamental design for a muzzle brake, as shown.
